UNITED STATES PATENT OFFICE.

A. A. WASHBURN, OF ST. JOHNSVILLE, NEW YORK.

WASHING-MACHINE.

Specification of Letters Patent No. 27,249, dated February 21, 1860.

To all whom it may concern:

Be it known that I, A. A. WASHBURN, of St. Johnsville, in the county of Montgomery and State of New York, have invented a new 5 and Improved Washing-Machine; and I do hereby declare that the following is a full, clear, and exact description of the same, reference being had to the accompanying drawing, forming a part of this specification, in 10 which—

Figure 1 represents a longitudinal vertical section of this invention. Fig. 2 is a plan or top view of ditto.

Similar letters in both figures refer to corresponding parts.

This invention relates to certain improvements in that class of washing machines in which a concave swinging tub, and a stationary washboard, together with two pounders, is employed; and the invention consists 20 in arranging in the wash-board two fluted rollers, to operate in combination with the corrugated bottom of the tub and with pounders cut out so as to correspond to the 25 rollers for the purpose of facilitating the rubbing and squeezing of the clothes without injury to the same, and this invention consists also in combining with the swinging tub a counterpoise, whereby the exertion 30 necessary to keep the tub in motion is considerably reduced.

To enable those skilled in the art to make and use my invention I will proceed to describe it.

35 A represents a concave tub suspended from a pin, *b*, that rests on two standards, *c*, and said tub is provided with two handles, *B*, which serve to impart to the same a swinging motion. The bottom, *C*, of the tub

is corrugated, and secured in its center is 40 the wash-board, *D*, which consists of two upright slats, *d*, which are secured to the standards, *c*, by means of the pin, *b*, and another pin, *b'*, which latter passes through the top of the standards and of the slats, as 45 clearly shown in Fig. 2. The slats are connected at the lower end by means of a cross brace, *f*, and by another brace, *g*, at a small distance below the pin, *b*. Between the two braces are the corrugated rollers, *E*, arranged so as to rotate freely on their pivots, 50 *h*. The pounders, *F*, are firmly secured to the bottom of the tub at equal distances from its center, and the inner surfaces of said pounders form concaves, *i*, to correspond to the corrugated rollers. On the top of the tub, and secured to the same by a semi-circular arc, *G*, is a counterpoise, *H*, the momentum of which assists materially 55 in operating the tub.

The tub is filled with water and soap-suds, as indicated in Fig. 1, and the clothes are placed into the water and between the pounders and the rollers and by imparting to the tub a swinging motion the washing is 60 65 effected.

What I claim as new, and desire to secure by Letters Patent, is:—

The arrangement of the fluted rollers, *E*, and the stationary wash-board, *D*, in combination with the corrugated bottom of the tub and with the concaves, *i*, in the pounders, *F*, substantially as and for the purpose specified.

A. A. WASHBURN.
